(57) **CLAIM**

I claim the ornamental design for a range hood, as shown and described.

DESCRIPTION

FIG. 1 is a top plan view of a range hood, showing my new design;

FIG. 2 is a bottom plan view thereof;

FIG. 3 is a front elevational view thereof;

FIG. 4 is a rear elevational view thereof;

FIG. 5 is a left side elevational view thereof, the right side being a mirror image of the right side;

FIG. 6 is a front perspective view of the range hood of my design; and,

FIG. 7 is rear perspective view of the range hood of my design.

The broken line showing of environmental structure is for illustrative purposes only and forms no part of the claimed design.
